Attorneys:

UNITED STATES PATENT OFFICE.

FRANK W. KNOWLTON, OF MOUNT VERNON, NEW YORK.

EASEL.

Application filed January 19, 1924. Serial No. 687,244.

To all whom it may concern:

Be it known that I, FRANK W. KNOWLTON, a citizen of the United States, residing at Mount Vernon, in the county of 5 Westchester and State of New York, have invented an Easel, of which the following is a specification.

My invention is an improvement in easels of that particular type supporting a drawing-board for the convenience of a person using the same.

The primary object of my invention is to provide an easel that is serviceable more especially as an article of school furniture 15 for use in teaching children in the graded schools, to be used by the scholars as well as the teacher, including in the present instance an arrangement by which the sheets of drawing-paper in attaching them to the 20 board are punctured for convenience in binding them together.

A further object of my invention is to provide an easel of this general type in which the drawing-board may be readily 25 and conveniently adjusted to different inclinations to suit the person using the same; the construction and assemblage of the parts constituting the easel being such that it may be built by one of ordinary skill in the use 30 of tools, as for instance by school children having a limited training in this respect.

With these principal objects in view my invention consists in the particular construction of the framework of the easel to provide for an adjustment of the inclination of 35 the drawing-board, and in the particular construction of the drawing-board forming an essential part of the easel for the purpose intended; all as hereinafter described and 40 specifically set forth in the claims.

In the accompanying drawings:

Fig. 1. is a perspective view of my improved easel.

Fig. 2 is a front elevation thereof.

Fig. 3 is a vertical sectional view through the center of the easel.

Fig. 4 is a detail sectional view through the lower portion of the drawing-board to show a plan view of the ledge on said board.

Fig. 5 is an enlarged detail sectional view illustrating the construction of the upper part of the drawing-board.

In carrying out my invention I construct a framework comprising side pieces 6

spaced a suitable distance apart according to the width of easel desired, and brace these side pieces by means of a lower horizontally disposed board or shelf 7, an intermediate face-board 8 and a rear cross-piece 9, the latter being preferably located near the upper ends of said side pieces, and to more firmly support the completed structure in upright position foot-pieces 10 are attached to the lower ends of the side pieces to extend readward therefrom. In the present instance the forward edge of the upper portion of each side piece 6 is cut away to form a series of ledges or steps 6^a 6^b 6^c for adjustment of the inclination of the drawing-board as hereinafter explained, the ledges or steps on one of the side pieces being in horizontal planes with the corresponding or companion ledges or steps on the other side piece. The frame is also provided with shelves 11 at opposite sides thereof suitably secured to the side pieces 6, and of course additional shelves may be provided as well as drawers (not shown) such as commonly employed in structures of this kind.

As the easel is more especially designed for use in a school-room for drawing and other work employed in teaching the pupils the board 12 forming the front thereof is herein termed a drawing-board and is hinged at its lower end to the upper edge of the face-board 8 of the frame, being of less width than the distance between the side pieces 6 to swing back and forth between the same, and as the hinges, 13, are attached to the rear side of said drawing and face boards the forward movement of the drawing-board is limited to the upright position (indicated in dotted lines Fig. 3) by contact of the meeting edges—its rearward movement being limited by the cross-piece 9 of the frame. To support or hold the drawing-board at an intermediate position, and thus provide for an adjustment of its inclination to suit a person using the easel, a cross-bar or rod 14 is placed across the frame from one step to another in the rear of said drawing-board for it to rest against. In the present instance I have provided for three adjustments but it will be obvious that the degree of inclination of the drawing-board in fixed position may be varied to a greater extent by providing additional ledges or steps, and it will

be understood that the cross-bar or rod 14 is removable, that is loose upon the ledges or steps, so that it may be shifted from one set to another. The stepped construction of 5 the side pieces of the frame of the easel not only provides for adjusting the inclination of the drawing-board by using the cross-bar or rod 14 in the manner described but these ledges or steps also provide a convenient 10 means for aiding one in drawing horizontal lines on the board or drawing paper attached thereto, in such instance the ruler or rod, as 15 (dotted lines Figs. 2 and 3), rests upon the forward ends of companion ledges 15 or steps of the series corresponding with the 15 location of the line. In front of the drawing-board at the lower edge thereof is a narrow ledge 16, and upon this may be placed loosely a glass strip 17 to receive 20 utensils used in drawing, &c., and to aid in drawing vertical lines the upper surface of the ledge 16 is marked with a scale (Fig. 4) cooperating with a corresponding scale at the upper end of the drawing-board (Fig. 2), said scales serving as a guide for the 25 rod or ruler 15, as will be understood.

The writing-face of the drawing-board may be a material from which marks may be erased, for instance what is termed a 30 blackboard may be used, but I prefer to make the board of wood to receive a sheet of drawing-paper, as 18, and instead of the paper being attached to the board by thumbtacks, as usually practised, I provide means 35 that will not only secure the drawing-paper to the board but will puncture the same for convenience in binding a number of sheets together by a string or a conventional loose-leaf binder. For the purposes mentioned 40 a detachable strip 19 is secured to the upper edge of the drawing-board by pins 20, said pins being dowelled into the strip and glued thereto with their outer ends sharpened or pointed to pierce the sheet of paper, the 45 upper edge of the board 12 being provided with holes 21 to receive the pins. The pins are spaced apart as shown in Fig. 2 of the drawings, but if the sheets of drawing paper are to be bound in a loose-leaf binder the 50 pins 20 may be arranged accordingly. The sheet of drawing-paper is attached to the board as clearly illustrated in Fig. 5; that is, a portion is folded over the upper edge of the board 12 so that said sheet of paper 55 will lie against said board, as illustrated in Fig. 1, and the removable strip 19 is then secured in place by entering the pins 20 into the holes 21, puncturing the sheet of drawing-paper in the operation.

60 Aside from the adjustment of the inclination of the drawing-board and attaching the drawing-paper to said board the easel is used in the same manner as other easels of this general type, but the particular construction of the easel shown and described

not only provides a simple and effective arrangement for adjusting the drawing-board and attaching sheets of paper to the same but also provides an article of school furniture that can be constructed at small expense and which will be of special usefulness in teaching children in the primary grades. Furthermore, attention may be directed to the utility of the ledge 16-17 in addition to that of holding drawing utensils; that is it will also serve to keep a child's clothes from coming in contact with the drawing, the glass-top 17 also allows cleaning to be done more readily, and for the same purpose glass tops may be placed 70 on the shelves 11, the latter also receiving drawing utensils, paints, &c. When the easel is made for schools of the primary grade, as for instance kindergarten work, I propose to decorate the side pieces 6-6 with 75 pictures pleasing to children, particularly those illustrating fairy stories, but as it is customary to finish articles of furniture in this manner no stress is laid on this feature of the complete device and it is not so illustrated in the drawings.

The easel is not only used for the purpose of making drawings but is also well adapted for that method of teaching whereby concrete work in arithmetic, geography, history, language, etc., may be carried out.

I claim:

1. An easel comprising a frame formed of spaced apart upright side pieces having stepped horizontal ledges at the upper part of the forward edges thereof, a cross-piece between said side pieces near their lower ends, a face-board attached between the forward edges of the side pieces above the cross-piece and below the aforesaid ledges, and a cross-bar at the rear end of the frame near the upper end thereof; together with a drawing-board hinged to the upper edge of the face-board to swing between the side pieces and limited in its rearward movement by the cross-bar, the hinges being at the rear of the face-board and drawing-board so that the meeting edges limit the forward movement of the latter to upright position, a forwardly projecting ledge attached to the lower end of the drawing-board, and a removable rod to rest on the ledges of the side pieces across the back of the drawing-board to support it at an inclination.

2. An easel comprising a frame formed of spaced apart upright side piece having stepped horizontal ledges at the upper part of the forward edges thereof, a cross-piece between said side pieces near their lower ends, a face-board between the forward edges of the side pieces above the cross-piece and below the aforesaid ledges, and a cross-bar at the rear end of the frame near the upper end thereof; together with a drawing-board hinged to the upper edge of the

face-board to swing between the side pieces and limited in its rearward movement by the cross-bar, a detachable strip at the upper edge of the drawing-board having spaced apart pins engaging holes in the edge of said drawing-board to puncture and hold a sheet of paper thereon, and a removable

rod to rest on the ledges across the back of the drawing-board to support it at an inclination, the ledges projecting forwardly to receive a ruler across the front of the drawing-board for the purpose of drawing horizontal lines. ¹⁰

FRANK W. KNOWLTON.
